UNITED STATES PATENT OFFICE.

WILLIAM H. WILKIE, OF DETROIT, MICHIGAN.

TRAY FOR LUNCH-BOXES.

1,353,689.

Specification of Letters Patent. Patented Sept. 21, 1920.

Application filed December 9, 1919. Serial No. 343,534.

To all whom it may concern:

Be it known that I, WILLIAM H. WILKIE, a citizen of the United States, residing at Detroit, in the county of Wayne and State 5 of Michigan, have invented certain new and useful Improvements in Trays for Lunch-Boxes; and I do hereby declare the following to be a full, clear, and exact description of the invention, such as will enable others 10 skilled in the art to which it appertains to make and use the same, reference being had to the accompanying drawings, and to the letters and figures of reference marked thereon, which form a part of this specification. 15

This invention relates to new and useful improvements in a tray and receptacle for holding a piece of pie for a lunch box, and consists of a simple and efficient device of 20 this character having various details of construction, combination and arrangement of parts which will be hereinafter fully described, shown in the accompanying drawing and then specifically defined in the appended claim. 25

My invention is illustrated in the accompanying drawings which, with the letters of reference marked thereon, form a part of this application, and in which:

30 Figure 1 is a perspective view of the blank.

Fig. 2 is a like view of the pan separated, Fig. 3 is a vertical section, and

35 Fig. 4 is a fragmentary, perspective view of one corner of the device.

Reference now being had to the details of the drawings by letter:

A designates a preferably substantially triangular-shaped blank formed advantageously of metal, scored along the lines B to form flanges C extending along the sides of the triangular-shaped blank. Said triangular-shaped blank is notched, as shown at a, at the ends of the base of the triangular-shaped blank, and also at b, b, toward

the apex of the triangular-shaped blank, forming a tab D, as shown.

The flanges c, c, c are bent up into a position at right angles with the body of the blank A. The tab D is then bent up and the 50 side portions thereof are bent over the exterior face of the flanges c, c, as shown in Fig. 2.

In connection with the tray, as thus formed, I provide a cover E of generally 55 triangular shape, and provided with side flanges and an end flange at the base of the triangular-shaped cover. Said triangular cover E has an apex, removed as shown in Fig. 2, so that said side flanges of the cover 60 are spaced at this end, so as to receive between them the flap D, thus permitting the insertion of the finger to pull down the flap, when desired to display the contents of the tray at this end. 65

What I claim to be new is:

A triangular-shaped tray comprising a triangular-shaped blank bent along the longitudinal sides thereof to provide side flanges, and also bent along the base of said 70 triangular-shaped blank to provide a base flange, said blank being notched at the ends of the base flange and toward the apex of said triangular shaped blank, said notches, at the apex portion, providing a flap, said 75 flap being bent upward and the sides of said flap being bent against the exterior face of the side flanges, in combination with a triangular-shaped cover, the apex of which is cut away, said cover being provided with 80 side flanges, said side flanges being adapted to bear against the side flanges of the tray, the apex flap of the tray being exposed, when the cover is in place, thus permitting said flap to be bent downward to expose the 85 contents of the tray.

In testimony whereof I hereunto affix my signature.

WILLIAM H. WILKIE.
